PIEZOELECTRIC TRANSFORMERS

BACKGROUND OF THE INVENTION

This invention relates to a piezoelectric transducer, more particularly to a piezoelectric transformer having novel electrode construction.

As is well known in the art the piezoelectric transformer generally comprises an elongated rectangular ceramic body of barium titanate (BaTiO_3) or lead zirconate titanate or the like. One-half the length of the ceramic body, that is the driving portion, is polarized in the direction of thickness while the remaining half, i.e., the generating portion is polarized in the direction of length. A pair of input electrodes of silver for example is applied by firing on the opposite surfaces of the driving portion and an output electrode is secured by firing to the end surface of the generating portion. Lead wires are soldered to the pair of input electrodes and the output electrode, respectively. Since these electrodes are comprised by extremely thin layers and since the piezoelectric transformer itself is a mechanical vibrating body there are such difficulties that the soldered joints are destroyed to damage the electrode surfaces and that the lead wires are broken. Although the lead wires may be bonded to the electrodes by utilizing a suitable binder, such bondings are often loosened or disengaged during slight elongation and contraction of the ceramic body due to the heat generated during the operation of the piezoelectric transformer. For this reason, use of the binder is not advantageous.

SUMMARY OF THE INVENTION

It is therefore an object of this invention to provide an improved piezoelectric transformer having a novel electrode construction according to which the lead wire as well as the electrical or mechanical connection between the lead wire and the electrode is prevented from being damaged due to the mechanical vibration of the piezoelectric transformer.

Another object of this invention is to provide a novel electrode construction for a piezoelectric transformer which does not use any bonding agent and wherein the mechanical connection of the electrode will never be loosened by the temperature rise of the piezoelectric transformer.

To accomplish these and another objects, according to this invention there is provided an improved piezoelectric transformer comprising a body of ceramic, a pair of lead wires with one portion thereof mounted on the surface of the driving portion of the ceramic body, a pair of rectangular clamping plates of insulative rubber to cover said mounted portions of the lead wires and extending in the direction of the width of the driving portion, means for simultaneously clamping the opposite ends of the clamping plates, and an electrode comprising a frame shaped electroconductive rubber fitted over the end of the generating portion of the ceramic body. According to this invention, the insulative rubber plates or clamping plates may be made of a conventional electroconductive rubber having a resistivity of the order of $10^1 - 10^3$ ohm-cm or a conductive rubber having a resistivity of the order of 0.2 - 5 ohm-cm and containing copper wires. When constructed with these materials, the clamping plates are provided with

longitudinal grooves or openings to accommodate end portions of the lead wires.

Further, according to this invention the driving electrodes may comprise a pair of electrode plates of conductive rubber covering substantially the entire surface area of the driving portion of the ceramic body. Each electrode plate is provided with a stem extending in the longitudinal direction of the electrode plate, said stem serving to receive a lead wire for external connection. Further, the stem may take the form of a projection on the upper surface of the electrode plate. According to another feature of this invention, the electrode plates are urged against the surface of the ceramic body by means of a pair of opposing stays on both sides of the ceramic body and a pair of supporting rods of elastic electroconductive rubber. The ends of these supporting rods are firmly clamped by the stays so that the rods are urged against the electrode plates.

BRIEF DESCRIPTION OF THE DRAWINGS

The invention can be more fully understood from the following detailed description taken in conjunction with the accompanying drawings in which:

FIG. 1 is a perspective view of one embodiment of the novel piezoelectric transformer;

FIG. 2 is a sectional view of a portion of the piezoelectric transformer, taken along a line 2 - 2;

FIG. 3 is a sectional view corresponding to FIG. 2 of a modified piezoelectric transformer;

FIG. 4 shows characteristic curves showing the relationship between high voltage current and high voltage output of a conventional piezoelectric transformer and of the novel piezoelectric transformer;

FIG. 5 shows another modified piezoelectric transformer;

FIG. 6 shows still another modification of this invention;

FIG. 7 is a perspective view of modified electrode plates utilized in the piezoelectric transformer shown in FIG. 6 and

FIG. 8 is a perspective view of yet another embodiment of this invention.

DESCRIPTION OF THE PREFERRED EMBODIMENTS

Referring now to the accompanying drawing, the piezoelectric transformer shown in FIGS. 1 and 2 comprises a rectangular plate shaped ceramic body 16 having one-half, that is driving portion 12, polarized in the direction of thickness and the other half, that is the generating portion 14, polarized in the axial direction. Opposite surfaces of the driving portion 12 are covered by silver electrode layers 18 and 20, shown exaggerated. One end 22a and 24a (see FIG. 2) of each of input lead wires 22 and 24 connected to a driving circuit, not shown, are mounted on the silver electrode layers 18 and 20 to oppose each other and these ends are urged against the surface of the silver electrode layers 18 and 20 by means of a pair of rectangular clamping plates 26 and 28 disposed transversely of the ceramic body. These clamping plates are made of an elastic insulating material such as natural or synthetic rubber and their inner surfaces are provided with grooves 30 and 32 to accommodate the ends 22a and 24a of input lead wires 22 and 24. Opposite ends of the clamping plates 26 and 28 are firmly secured to the ceramic body by means of a pair of U-shaped clamps 34 and 36.

Advantageously, clamps 34 and 36 are molded from elastic insulative synthetic resinous material or made of spring metal strips covered by insulating coatings. In the case of a piezoelectric transformer operating at a λ mode, it is preferable to locate the clamps 26 and 28 1/4 spaced apart from the left hand end of the ceramic body, where l represents the total length of the ceramic body. These positions, that is the intermediate points along the length of the driving portion, correspond to the nodes of the mechanical oscillation of the ceramic body and do not vibrate substantially so that application of additional weight on the ceramic body does not affect in any way the natural frequency of the ceramic body as well as its oscillation characteristics.

On the outer end of the right hand half or the generating portion of the ceramic body 16 is provided a cap shaped output electrode 40 of electroconductive rubber having a rectangular recess 38 corresponding to the cross-sectional configuration of the generating portion. The output electrode 40 can also be formed in the form of a conductive band and is formed with a laterally extending thin stem 42. The outer end of this stem 42 is connected to one end of a selenium rectifier 46 supported by a stationary arm 44, as shown in FIG. 1. Alternatively, as shown in FIG. 5, one end of an output lead wire 48 may be firmly wound about the outer end of the stem 42.

FIG. 3 shows a modified configuration of the clamping plates, wherein clamping plates 49 and 50 are molded from conductive rubber and are provided with longitudinal narrow openings 52 and 54 near the center thereof to snugly receive end portions 22a and 24a of input lead wires 22 and 24.

As can be clearly noted from foregoing description according to the novel electrode constructions shown in FIGS. 1 to 3 the lead wires are more firmly secured to the electrode layers than the prior art electrode construction so that lead wires would never be loosened or disengaged by the vibration of the ceramic body 16. Further, since according to this invention lead wires are elastically clamped by clamping plates made of elastic material such as rubber, vibrations transmitted to lead wires are efficiently absorbed thus protecting them against breakage.

FIG. 4 shows comparison of high voltage current viz high output voltage characteristics of a prior art transformer (curve b) and of the novel piezoelectric transformer (curve a). Characteristic curve a shown in FIG. 4 was obtained from a piezoelectric transformer operating at the $\lambda/2$ mode and provided with the electrode construction shown in FIG. 1. As can be noted from this curve, although clamping plates 26 and 28 are not located at the nodal point of the vibration of the ceramic body 16, the high output values are not varied appreciably showing only 5 percent decrease when compared with the prior art piezoelectric transformer.

FIG. 5 illustrates a modified clamping device 56 different from that shown in FIGS. 1 and 2. Clamping device 56 comprises rigid insulator members 58 and 60 of synthetic resin such as formaldehyde resin, epoxide resin, acrylic resin and the like and extending transversely of the ceramic body 16 along the surface of clamping plates 26 and 28, a pair of screws 62 and 64 threaded through openings at the opposite ends of the rigid members 58 and 60, and nuts 66 engaging screws 62 and 64. This clamping device 56 and corresponding

to clamping plates 26 and 28 (in the case of FIG. 3, clamping plates 49 and 50) is mounted at a point 1/4 separated from the left hand end of the ceramic body or at the nodal point of the vibration of the ceramic body operating at the λ mode. Although not shown in the drawing the clamping device 56 urging clamping plates 26 and 28 or 49 and 50 against the ceramic body is suitably mounted on the stationary portion to support the ceramic body.

FIG. 6 shows a modified embodiment of this invention wherein above described clamping plates 26, 28 or 49, 50 are replaced by a pair of electrode plates 70 and 72 of electroconductive rubber and covering substantially the entire surface of the driving portion 12 of the ceramic body 16. One side of each of electrode plates 70 and 72 is provided with narrow integral stems or extensions 74 and 76 extending in the longitudinal direction of the ceramic body. End portions 22a and 24a of input lead wires 22 and 24 are firmly wrapped about free ends of stems 74 and 76. Alternatively, the outer ends of the stems may be securely fixed to the stationary portion.

In a modified electrode plate 70 shown in FIG. 7 a projection 78 is formed on the upper surface thereof and the input lead wire is connected to the projection 78. The modifications shown in FIGS. 6 and 7 eliminate silver electrode layers 18 and 20, but if required such electrode layers may be used in conjunction with electrode plates 70 and 72. Driving arrangement of the ceramic body 16 through electrode plates 70 and 72 slightly increases the electrical resistance on the input side but use of electrode plates 70 and 72 not only increases the contact area for the ceramic body but also absorbs the vibration energy transmitted to the input lead wires 22 and 24 by the resiliency of the electrode plates thus preventing breakage fault of the lead wires.

FIG. 8 illustrates still another modification of this invention wherein electrode plates 70 and 72 applied on the opposite sides of the driving portion 12 of the ceramic body 16 are supported by a pair of stationary stays 80 and 82 through a pair of supporting rods 84 and 86 of resilient electroconductive rubber. Input lead wires 22 and 24 are electrically connected to electrode plates 70 and 72, respectively by wrapping one end of each of the lead wires around supporting rods 84 and 86 near stays 80 and 82. With this construction, vibrations due to the operation of the piezoelectric transformer are absorbed by the resiliency of the supporting rods 84 and 86 and thus preventing them from being transmitted to input lead wires connected to the outer ends of the supporting rods. In this manner input lead wires are well protected against breakage.

Although the invention has been shown and described in terms of some preferred embodiments thereof it should be understood that the invention is not limited to these embodiments and that many modifications may be made within the true spirit and scope of the invention as defined in the appended claims. As used in the claims the term "rubber" will be understood to include any elastomer having the electric and mechanical properties specified.

What is claimed is:

1. A piezoelectric transformer comprising a rectangular plate-shaped ceramic body with one-half of its length polarized in the direction of thickness and the remaining half polarized in the axial direction, a pair of

input electrodes applied on the opposite surfaces of said one-half polarized in the direction of thickness, and an output electrode on the outer end of said remaining half polarized in the axial direction, the improvement which comprises an output electrode of conductive rubber, said output electrode being fitted over the outer end of said longitudinally polarized half of said ceramic body and having an integral stem extension adapted for connection to a lead wire remote from said output electrode.

2. A piezoelectric transformer comprising a rectangular plate shaped ceramic body with one half of its length polarized in the direction of thickness and the remaining half polarized in the longitudinal direction, a pair of input electrode plates of conductive rubber, said electrode plates covering and in direct electric contact with substantially the entire surface of said half polarized in the direction of thickness, means to fixedly secure said electrode plates to said ceramic body and adapted to support said ceramic body, and an output electrode of conductive rubber fitted over the outer end of said remaining half polarized in the longitudinal

direction.

3. The piezoelectric transformer according to claim 2 wherein said input electrode plates include integral means to connect said input lead wires to said electrode plates.

4. The piezoelectric transformer according to claim 3 wherein said integral means comprise axial extensions of said electrode plates.

5. The piezoelectric transformer according to claim 10 3 wherein said integral means comprise projections vertically extending from the surface of said electrode plates.

6. The piezoelectric transformer according to claim 15 2 wherein said clamping means comprises a pair of stationary stays spaced apart from said ceramic bodies and a pair of supporting rods arranged between respective stays and said electrode plates, said supporting rods being made of elastic conductive rubber and 20 wherein said input leads wires are connected to said supporting rods at portions thereof close to said stays.
